ALKYL 3-ACYLOXY-2-ALKENOATES AND HOMOPOLYMERS THEREOF

Lee A. Miller, Dayton, Ohio, assignor to Monsanto Chemical Company, St. Louis, Mo., a corporation of Delaware

No Drawing. Filed Oct. 30, 1959, Ser. No. 849,721

19 Claims. (Cl. 260—78.3)

The present invention relates to olefinic diesters and more particularly provides an improved process of preparing alkyl 3-acyloxy-2-alkenoates, especially the alkyl 3-acyloxyacrylates. The invention also provides certain valuable and hitherto unknown esters of 3-hydroxyacrylic acid. According to the invention the alkyl 3-acyloxy-alkenoates are prepared by the catalyzed addition reaction of an acetylenic carboxylic acid, say, alkyl 2-alkynoate with a monocarboxylic acid having a hydrogen ion concentration of less than 1.396×10^{-3} . The reaction takes place substantially according to the scheme:

where R is a radical corresponding to the carboxy-free residue of a carboxylic acid having an ionization constant of less than 1.396×10^{-3} , Y is an alkyl radical of from 1 to 5 carbon atoms, and Z is selected from the class consisting of Y, hydrogen, and aryl radicals of from 6 to 10 carbon atoms.

Examples of presently useful carboxylic acids, i.e., those having an ionization constant of less 1.396×10^{-3} are the alkanecarboxylic acids, the alkenecarboxylic acids and the aromatic hydrocarbon carboxylic acids broadly. Substituents may be present at the aliphatic chain and/or the aromatic nucleus of the carboxylic acid so long as the ionization constant of the acid is not greater than that of chloroacetic acid, i.e., 1.396×10^{-3} . Such substituents may be, e.g., halogen, nitro, alkoxy, hydroxy, aldehydo, carboalkoxy, amido, etc. The carboxylic acid may also be a cycloaliphatic acid or a heterocyclic acid having the above specified hydrogen ion concentration. Examples of the individual carboxylic acids which are useful for the present purpose are acetic acid, propionic acid, heptanoic acid, octanoic acid, decanoic acid, dodecanoic acid, stearic acid, benzoic acid, butyric or isobutyric acid, caproic acid, caprylic acid, 2-chlorobenzoic acid, 4-chlorobenzoic acid, 2-, 3- or 4-chlorocinnamic acid, 2-, 3- or 4-chlorophenylacetic acid, 2- or 3-chloropropionic acid, acrylic acid, 3-butenoic acid, cinnamic acid, 3,3-dimethylacrylic acid, diphenylacetic acid, 2,4-dinitrophenylacetic acid, 4-ethylbenzoic acid, 4-ethylphenylacetic acid, 2-, 3-, or 4-fluorobenzoic acid, 4-formic acid, 2-, 3-, or 4-hydroxybenzoic acid, 2-iodobenzoic acid, 2-, 3- or 4-methoxybenzoic acid, 2-isopropyl-1-naphthoic acid, 1- or 2-naphthoic acid, 3- or 6-methoxy-2-naphthoic acid, 2- or 4-nitrobenzoic acid, 2-, 3-, or 4-nitrocinnamic acid, 2-nitro-3-phenylpropionic acid, 2-, 3-, or 4-phenoxybenzoic acid, 2-phenylbenzoic acid, 11-dodecanoic acid, octadecenoic acid, 2-hexenoic acid, 4-methyl-2-pentenoic acid, 3-propylidenepropionic acid, pyridine-2-carboxylic acid, pyridine-3-carboxylic acid, pyridine-4-carboxylic acid, 2-furoic acid, 2-, 3-, or 4-toluic acid, valeric and isovaleric acid, vanillic acid, 1-, 2-, 3-, 4-, or 9-fluorenecarboxylic acid.

The presently useful alkyl alkynoates are for example, the alkyl propiolates such as the methyl, ethyl, propyl, isopropyl, butyl, tert-butyl, isobutyl, amyl, isoamyl, or methyl, ethyl, propyl, butyl or amyl tetrolates; the alkyl 2-pentynoates such as the methyl or butyl 2-pentynoate

2

or the ethyl or isopropyl 4-ethyl 2-pentynoate, the alkyl 2-hexynoates such as methyl or propyl 2-hexynoate; the arylpropiolates such as ethyl or amyl phenylpropionate or 2-, 3-, or 4-tolylpropionate and methyl or butyl α -naphthylpropionate; the alkyl 2-heptynoates such as ethyl or butyl 2-heptynoate or methyl and methyl or isobutyl 6-methyl 2-heptynoate; the alkyl 2-octynoates such as methyl or propyl 2-octynoate, etc.

Examples of compounds prepared according to the presently provided process are, e.g., methyl, ethyl, or amyl 3-benzoyloxyacrylate; ethyl, propyl or butyl 3-acetoxyacrylate; butyl, isoamyl or methyl 3-propionyl-oxyacrylate; isobutyl, methyl or ethyl 3-acryloyloxyacrylate; methyl, ethyl or isopropyl 3-propenoxyacrylate; methyl, ethyl or butyl 3-(2-, 3-, or 4-chlorobenzoyloxy)acrylate; ethyl, methyl or propyl 3-cinnamoyloxyacrylate; tert-amyl, isopropyl or methyl 3-diphenylacetoxymyacrylate; ethyl, methyl, or propyl 3-(1- or 2-naphthoyloxy)acrylate; butyl, amyl or ethyl 3-(2- or 4-nitrobenzoyloxy)acrylate; ethyl, methyl or amyl 3-(2-, 3-, or 4-phenoxybenzoyloxy)acrylate; ethyl, isoamyl or propyl 3-(3-phenylpropionyl-oxy)acrylate; ethyl, methyl or isobutyl 3-(2-hexenoxy)acrylate; ethyl, methyl or isoamyl 3-(2-furoxy)acrylate; isopropyl, amyl or methyl 3-(2-, 3-, or 4-toluoyloxy)acrylate; ethyl, methyl or propyl 3-(3-butenoyloxy)acrylate; propyl, butyl or methyl 3-dodecanoyloxyacrylate; methyl, butyl or isoamyl 3-(2-hexenoxy)acrylate, methyl or ethyl 3-acetoxy-2-butenoate; methyl or butyl 3-benzoyloxy-2-butenoate; butyl or ethyl 3-propionyloxy-2-pentenoate, butyl or methyl 3-(2-naphthoyloxy)-2-butenoate, amyl or butyl 3-butyoxy-2-pentenoate, methyl or ethyl 3-(4-toluoyloxy)2-pentenoate, amyl or isopropyl 3-acetoxy-2-hexenoate, ethyl or methyl 3-(9-fluorenoxy)-2-hexenoate, amyl or methyl 3-(4-chlorobenzoyloxy)-2-hexenoate, ethyl or methyl 3-(3-butenoyloxy)-2-hexenoate, methyl or ethyl 3-acetoxy-2-heptenoate, butyl or isopropyl 3-(4-ethylbenzoyloxy)-2-heptenoate, butyl or propyl 3-propionyloxy-2-octenoate, methyl or ethyl 3-cinnamoyloxy-2-octenoate, methyl or ethyl 3-acetoxy-3-phenylacrylate, methyl or isopropyl 3-propionyloxy-3-phenylacrylate, methyl or butyl 3-acetoxy-3-(2-tolyl)acrylate, ethyl or propyl 3-acetoxy-3-(4-ethylphenyl)acrylate, methyl or ethyl 3-propionyloxy-3-(2-naphthyl)acrylate, ethyl or propyl 3-acetoxy-3-(α -naphthyl)acrylate, butyl or methyl 3-(9-fluorenoxy)-3-phenylacrylate.

The presently provided process is particularly valuable in that it provides as new compounds the hitherto unknown alkenoyloxyacrylates, i.e., compounds of the structure:

55 wherein alkenyl designates an alkenyl radical of from 2 to 6 carbon atoms and Y is an alkyl radical of from 1 to 5 carbon atoms. These compounds are prepared according to the invention by the reaction of an alkenoic acid having from 2 to 6 carbon atoms with the alkyl propiolate. The alkyl 3-alkenoyloxyacrylates thus obtained polymerize to tough, rubbery solids upon standing at room temperature or heating at, say, a temperature of from 15° C. to 110° C. The polymerization may be accelerated, if desired, by the use of free radical-liberating agents, e.g., peroxidic compounds such as benzoyl peroxide or tert-butyl hydroperoxide, etc.

Solutions of the present homopolymeric alkyl 3-alkenoyloxy-acrylates are useful as coatings and give flexible films upon casting. This class of compounds is also valuable as copolymerizing monomers with, e.g., vinyl compounds such as the alkyl acrylates and methacrylates

3
or the vinyl aromatic compounds such as styrene or α -methylstyrene. They also serve as cross-linking agents in the manufacture of hard resins of very good mechanical properties from linear polyesters, polymeric diolefins, etc. They are also advantageously employed as biological toxicants, e.g., as bactericides, fungicides, insecticides, and as nematocides.

The invention also provides as new and valuable compounds the alkyl 3-acyloxyacrylates wherein the acyl radical is derived from a naphthoic acid or from a fluorenecarboxylic acid. The alkyl 3-naphthoyloxyacrylates are valuable as microbiological toxicants and as soil fungicides and the alkyl 3-fluorenoyloxyacrylates possess selective herbicide properties, and are particularly valuable for their preemergent effect.

Reaction of the monocarboxylic acid with the alkyl alkanoates takes place in the presence of basic or acidic catalysts. Basic catalysts useful in the process include organic bases such as pyridine, the quaternary ammonium salts or bases such as trimethylbenzylammonium hydroxide, the alkali and alkali metal hydroxides or basically reacting salts thereof such as sodium, potassium, lithium, calcium, or magnesium hydroxide, carbonates or acetate; alkali or alkali metal alcohoholates such as sodium methydate, etc. Examples of useful acidic catalysts are acid reacting metallic salts, such as cuprous or cupric, stannous or stannic, ferrous or ferric acetates, sulfates or chlorides, organic or inorganic acids such as acetic, sulfuric, phosphoric or oxalic acid, etc. While I prefer to use as a catalyst a material which is soluble in the mixture of carboxylic acid and propiolate, such solubility of the catalyst in the initial reactants is not a necessary property of the catalyst.

According to the invention the 3-acyloxyalkenoates are readily prepared by simply mixing the carboxylic acid with the alkynoate in the presence of either the acidic or basic catalyst and in the presence or absence of an inert diluent or solvent and allowing the resulting reaction mixture to stand at ordinary or increased temperatures until formation of the 3-acyloxyalkenoate has occurred. Useful solvents or diluents are, e.g., benzene, xylene, dioxane, dichlorobenzene or hexane. Depending on the nature of the individual carboxylic acid and of the catalyst employed, the addition reaction may occur under varying conditions of temperature and pressure. For optimum yields, it is advantageous to heat the reaction mixture at temperatures of, say, from approximately 60° C. to the refluxing temperature of the reaction mixture.

Inasmuch as molecular equivalents of the carboxylic acid and the alkynoate are involved in the formation of the 3-acyloxy-2-alkenoates, it is advantageous to employ stoichiometric proportions of the two reactants. If desired, however, any excess of either reactant may be employed since any unreacted material is readily separated from the product.

The alkyl 3-acyloxy-2-alkenoates are stable, rather high-boiling, viscous liquids or crystalline materials which are separated from the reaction mixture, in the event that there has been employed either an excess of one of the reactants or a diluent, by methods known to those skilled in the art, e.g., by fractional distillation, crystallization, etc.

The present invention is further illustrated by, but not limited to, the following examples.

Example 1

This example describes reaction of methyl propiolate with acetic acid to give methyl 3-acetoxyacrylate. Reaction was effected by heating at reflux a mixture consisting of 12.0 g. (0.2 mole) of 99.7% glacial acetic acid, 16.8 g. (0.2 mole) of methyl propiolate, 100 ml. of benzene and 1 ml. of dry pyridine. When there was no further evidence of reaction the solvent was removed from the reaction mixture by distillation in vacuo and the residue was distilled to give the substantially pure methyl 3-acetoxy-

4
acrylate, B.P. 41-43° C./0.3 mm., n_D^{25} 1.4489, and analyzing as follows:

5	Found	Calcd. for $C_6H_{10}O_4$
Percent C.....	50.18	50.00
Percent H.....	5.74	5.60

10 Infrared analyses of the compound confirmed the presence of both the

15 structures.

Example 2

A mixture consisting of 8.4 g. (0.1 mole) of methyl propiolate, 12.2 g. (0.1 mole) of benzoic acid, 1 ml. of pyridine and 75 ml. of benzene was heated at reflux for 12 hours. The reaction mixture was then evaporated in vacuo to give 17.6 g. (86% theoretical yield) of the substantially pure methyl 3-benzyloxyacrylate, M.P. 38-40° C. Distillation yielded the pure compound, B.P. 102-103° C./0.3 mm., M.P. 40-43° C. This material analyzed as follows:

30	Found	Calcd. for $C_{11}H_{10}O_4$
Percent C.....	64.44	64.07
Percent H.....	4.96	4.89

Example 3

35 This example describes the addition reaction of methyl propiolate with acrylic acid.

A mixture consisting of 9.2 g. (0.11 mole) of methyl propiolate, 7.2 g. (0.1 mole) of acrylic acid, 0.1 g. of hydroquinone, 2 drops of pyridine and 25 ml. of butanol was maintained under nitrogen in the absence of light at room temperature for 2 weeks. At the end of that time the reaction mixture was refluxed for 12 hours and evaporated at 70° C. under water pump vacuum. Distillation of the residue gave the substantially pure methyl 3-acryloyloxyacrylate, B.P. 54-55° C./0.1 mm., which analyzed 53.72% carbon and 5.29% hydrogen as against 53.84% and 5.16%, the respective calculated values. Infrared analyses showed the presence of the

and the carboxylate groupings.

Example 4

55 A mixture consisting of 21.0 g. (0.1 mole) of 9-fluorene-carboxylic acid, 8.4 g. (0.1 mole) of methyl propiolate, 150 ml. of benzene and 1 ml. of pyridine was heated at reflux for 12 hours. At the end of that time the solvent was removed in vacuo to give as residue 22.1 g. (75% theoretical yield) of the substantially pure methyl 3-(9-fluorenoyloxy)acrylate.

Example 5

65 A mixture consisting of 9.2 g. (0.11 mole) of methyl propiolate, 17.2 g. (0.1 mole) of 2-naphthoic acid, 100 ml. of benzene and 1 ml. of pyridine was stirred at reflux under nitrogen for 12 hours. The homogenous, deep red reaction mixture was evaporated to dryness to give a solid which upon recrystallization from absolute methanol gave the substantially pure methyl 3-(2-naphthoyloxy)acrylate, M.P. 84-86° C. Repeated recrystallization from methanol gave the pure compound, M.P. 89-90° C., which analyzed 70.03% carbon and 4.98% hydrogen as against 70.30 and 4.72%, the respective calculated values.

5

Example 6

This example shows testing of the methyl 3-(2-naphthoxyloxy)acrylate of Example 5 as a soil fungicide. In this test method, naturally-infested soil fortified with fungi that incite root rots, stem cankers, seedling blights, and seed decay is treated with a test chemical and incubated in a sealed container for a period of 24 hours. Seeds are sowed in the treated soil which is then incubated at 70° F. for 48 hours before being removed to greenhouse benches. Disease assessments are made two weeks later.

A uniform supply of infested soil containing the following organisms was prepared.

Rhizoctonia solani
Fusarium oxysporum f. vasinfectum
Sclerotium rolfsii
Verticillium albo-atrum
Pythium ultimum

A 6 ml. aliquot of a 1% stock solution of a test chemical is pipetted into a jar containing 600 g. of infested soil. This initial application rate is 100 p.p.m. or approximately 200 pounds per 6" acre. The jar is sealed and the contents thoroughly mixed by vigorous shaking. The treated soil is incubated at 70° C. and 24 hours later is transferred to 4" pots. Fifteen cotton and cucumber seeds are sowed in each pot. The seeded pots are then incubated at 70° F. and at a high relative humidity (96-98%) to assure activity of the organism in the soil. Forty-eight hours later the pots are removed to the greenhouse.

Two weeks later the number of seedlings emerged and the number remaining healthy are recorded. The percent emergence and disease incident is based on the inoculated, untreated and the sterile soil treatments. The following rating scale is used:

Rating	Number of Healthy Plants
E=Excellent	26-30
P=Promising	19-25
F=Fair	11-18
N=No Good	10 or less

Employing the presently provided methyl 3-(2-naphthoxyloxy)acrylate an excellent rating was thus obtained. Repetition of the testing at a 30 p.p.m. concentration also gave very good results.

Example 7

This example shows evaluation of the methyl 3-(9-fluorenoxyloxy)acrylate of Example 4 as a preemergent herbicide. Briefly, the chemical is applied in spray form to soil seeded to representative grasses and broad-leaf plants.

Aluminum pans, 13" x 9" x 2", were filled with a good grade of top soil which had been screened through a 1/4" wire mesh and mixed with sand in a preparation of two parts of the top soil to one part of the sand. The soil surface was then compacted to a depth of 3/4" from the top of the pan. Twenty seeds each of wild oats, crab grass, rye grass, mustard and pigweed were then scattered on the soil surface and covered with soil to the pan top.

The present herbicidal solution was prepared by dissolving 0.4 g. of the methyl 3-(9-fluorenoxyloxy)acrylate in 20 cc. of acetone. Ten ml. of this solution was diluted with water to 30 cc. Application of this quantity of the solution to said pans is calculated to correspond to the use of 25 lbs. of the test compound per acre. The planted pans were then placed in an exhaust hood and sprayed first with 30 cc. of an aqueous solution of a liquid fertilizer and 0.1% solution of octamethyl pyrophoramide. The liquid fertilizer was employed to give a uniform nutrition level and the amide was employed to prevent insect injury. Two pans were then respectively

6

sprayed with the 25 lbs. per acre solution of the test compound. One of the pans which had been planted and treated with the liquid fertilizer and octamethyl pyrophoramide in the same manner was set aside to be used as a "blank." The three pans were then placed in 1/2" of water and allowed to absorb moisture through perforated bottoms until the soil surface was completely moist. The pans were then transferred to a wet sand bench in the greenhouse, and maintained there for ten days under ordinary conditions of sunlight and watering.

Observation of the pans at the end of that time showed that the pan which had been sprayed with the 25 lbs. per acre solution of the methyl 3-(9-fluorenoxyloxy)acrylate indicated complete to very pronounced suppression of crab grass and pigweed; however, the wild oats, rye grass, and mustard had emerged and showed no evidence of phytotoxicity. Also, all of the seeds which had been planted in the pan which had not been sprayed with the methyl 3-(9-fluorenoxyloxy)acrylate had emerged and the plants were in excellent condition. Accordingly, when used at the rate of 25 lbs. per acre, the methyl 3-(9-fluorenoxyloxy)acrylate is an unusually effective pre-emergent herbicide in that it prevents emergence and growth of crab grass and pigweed without having any adverse effect on wild oats, rye grass, and mustard.

Example 8

The methyl 3-acryloyloxyacrylate of Example 3 was allowed to stand overnight at room temperature in the absence of an inhibitor of polymerization. At the end of that time it was found to have been converted into the homopolymer, a tough rubbery solid. Application of a solution of the homopolymer in a volatile solvent to wood slats gave, upon volatilization of the solvent, a tenuous flexible coating.

What I claim is:

1. The process which comprises heating a mixture consisting essentially of an alkyl 2-alkynoate of the formula $ZC\equiv COY$ where Y is alkyl of from 1 to 5 carbon atoms and Z is selected from the class consisting of Y, hydrogen and hydrocarbon aryl of from 6 to 10 carbon atoms, and a monocarboxylic acid having a hydrogen ion concentration of less than 1.396×10^{-3} , an inert diluent and a basic catalyst, and recovering an alkyl 3-acyloxy-2-alkenoate of the formula

in which R is a radical corresponding to the carboxy-free residue of said carboxylic acid and Z and Y are as herein defined.

2. The process which comprises heating a mixture consisting essentially of an alkyl propiolate having from 1 to 5 carbon atoms in the alkyl, a monocarboxylic acid having a hydrogen ion concentration of less than 1.396×10^{-3} , an inert diluent and a basic catalyst and recovering an alkyl 3-acyloxyacrylate of the formula:

60 wherein R is a radical corresponding to the carboxy-free residue of said carboxylic acid and Y is alkyl of from 1 to 5 carbon atoms.

3. The method which comprises heating, in the presence of a basic catalyst, an alkyl propiolate having from 1 to 5 carbon atoms in the alkyl radical with an alkanoic acid and recovering an alkyl 3-acyloxyacrylate having from 1 to 5 carbon atoms in the alkyl radical.

4. The method which comprises heating in the presence of a basic catalyst an aromatic hydrocarbon carboxylic acid with an alkyl propiolate having from 1 to 5 carbon atoms in the alkyl radical and recovering an alkyl 3-aryloxyacrylate having from 1 to 5 carbon atoms in the alkyl radical.

75 5. The method which comprises heating, in the pres-

ence of a basic catalyst, an alkene monocarboxylic acid having from 2 to 6 carbon atoms in the alkylene radical with an alkyl propiolate having from 1 to 5 carbon atoms in the alkyl radical and recovering an alkyl 3-alkenoyloxyacrylate having from 1 to 5 carbon atoms in the alkyl radical and from 2 to 6 carbon atoms in the alkenoyl radical.

6. The process which comprises heating methyl propiolate with acetic acid in the presence of a basic catalyst and recovering methyl 3-acetoxyacrylate from the resulting reaction product.

7. The process which comprises heating methyl propiolate with benzoic acid in the presence of a basic catalyst and recovering methyl 3-benzyloxyacrylate.

8. The process which comprises heating methyl propiolate with acrylic acid in the presence of a basic catalyst and recovering methyl 3-acryloyloxyacrylate.

9. The process which comprises heating methyl propiolate with 9-fluorenecarboxylic acid in the presence of a basic catalyst and recovering methyl 3-(9-fluorenoyl)oxyacrylate.

10. The process which comprises heating methyl propiolate with 2-naphthoic acid in the presence of a basic catalyst and recovering methyl 3-(2-naphthoyloxy)acrylate.

11. An alkyl 3-alkenoyloxyacrylate having from 1 to 5 carbon atoms in the alkyl radical and from 2 to 6 carbon atoms in the alkenoyl radical.

12. The homopolymer of an alkyl 3-alkenoyloxyacry-

late having from 1 to 5 carbon atoms in the alkyl radical and from 2 to 6 carbon atoms in the alkenoyl radical.

13. Methyl 3-acryloyloxyacrylate.

14. Homopolymeric methyl 3-acryloyloxyacrylate.

15. An alkyl 3-naphthoyloxyacrylate having from 1 to 5 carbon atoms in the alkyl radical.

16. Methyl 3-(2-naphthoyloxy)acrylate.

17. An alkyl 3-fluorenoyloxyacrylate having from 1 to 5 carbon atoms in the alkyl radical.

18. Methyl 3-(9-fluorenoyloxy)acrylate.

19. A compound of the formula

in which X is selected from the class consisting of alkenyl radicals of from 1 to 5 carbon atoms, and the naphthyl and fluorenyl radicals and Y is an alkyl radical of from 1 to 5 carbon atoms.
